UNITED STATES PATENT OFFICE.

FRANK HENRY RAAZ, OF EL CAMPO, TEXAS.

PLOW.

Application filed April 24, 1922. Serial No. 556,207.

To all whom it may concern:

Be it known that I, FRANK H. RAAZ, a citizen of the United States, residing at El Campo, in the county of Wharton and State of Texas, have invented a new and useful Plow, of which the following is a specification.

The object of this invention is to provide novel means whereby, in a wheel-mounted plow, the frame of the machine may be raised or lowered at will.

In the accompanying drawings:—

Figure 1 shows in side elevation, a device constructed in accordance with the invention; Figure 2 is a front elevation; Figure 3 is a top plan; Figure 4 is a cross section on the line 4—4 of Figure 3; Figure 5 is a cross section on the line 5—5 of Figure 3; Figure 6 is a cross section on the line 6—6 of Figure 4.

The frame of the machine comprises a main bar or support 1, which is of rectangular cross section. Angle brackets 2 are mounted on the main bar 1 and are held thereon by U-bolts 3. Beams 4 extend across the main bar 1 and are secured at 5 to the brackets 2. The beams 4 are connected by a brace 30 supporting a seat 38. The rear ends of the beams 4 carry plow shares 6. The numeral 9 marks a head bar mounted on the beams 4. The head bar 9 forms a mounting for a draft hitch 22 which is adjusted by connecting means 23, and a lever 25 fulcrumed on one of the angle brackets 2.

A clamping sleeve 39 is held by a draw bolt 40 on the main bar 1 and carries a segment 41. A shaft 42 is mounted for rocking movement in the bar 1. A collar 43 is fixed to the shaft 42. A lever 44 is secured to or formed integrally with the collar 43 and is provided with a latch mechanism 45 adapted to cooperate with the segment 41. The collar 43 carries a segment 46. A hanger 47 is mounted to rock on one end of the shaft 42. A lever 48 is carried rigidly by the hanger 47 and is supplied with a latch mechanism 49 adapted to cooperate with the segment 46. A collar 50 is secured to the shaft 42 on the opposite side of the machine from the parts last above described. The collar 50 carries a segment 51. A hanger 52 is mounted to rock on the shaft 42 at the outer end of the collar 50 and carries a lever 53 provided with a latch mechanism 54 adapted to

cooperate with the segment 51. Ground wheels 55 are journaled on the hangers 52 and 47. The hangers 52 and 47 are provided with guards 56 shielding the inner ends of the hubs of the ground wheels 55.

When the lever 44 is swung, motion will be transmitted to the collar 43 which is fixed to the shaft 42. Motion will likewise be transmitted to the hanger 47, because the hanger 47 is locked to the collar 43 through the instrumentality of the latch mechanism 49 and the segment 46. Motion will likewise be transmitted to the hanger 52, because the hanger is connected to the shaft 42 through the instrumentality of the latch mechanism 54, the segment 51 and the collar 50. Thus, by a manipulation of the lever 44, both of the hangers 52 and 47 will be swung, and the frame of the machine will be lowered or raised, on both sides at once, with respect to the ground wheels 55.

The latch mechanism 49 may be disengaged from the segment 46 whereupon the lever 44 may be used to rock the hanger 47, thereby lowering the frame of the machine at one side thereof. The latch mechanism 54 may be disengaged from the segment 51 whereupon the lever 53 may be employed to rock the hanger 52 to the end that a raising or lowering of the frame, at the opposite side of the machine, may be brought about.

Generally stated, the implement comprises means for raising and lowering both sides of the frame at once; and means for raising and lowering either side of the frame, independently of the other.

Having thus described the invention, what is claimed is:—

1. In a device of the class described, a main member; a soil-engaging element; means for connecting the soil-engaging element to the main member; a shaft mounted to rock in the main member; hangers pivoted on the shaft; ground wheels carried by the hangers; means for locking both hangers for movement with the shaft; means for swinging either hanger independently of the other, on the shaft; and means for rocking the shaft, when the hangers are locked thereto, thereby to secure a swinging movement of both hangers simultaneously.

2. In a device of the class described, a main member; a soil-engaging element; means for connecting the soil-engaging element to the main member; a shaft mounted

to rock in the main member; a segment fixed to the main member; a collar fixed to the shaft; a lever fixed to the collar and cooperating with the first specified segment; a 5 segment carried by the hanger; a hanger mounted to rock on the shaft; a lever carried by the hanger and cooperating with the segment on the collar; a second collar fixed to the shaft; a second hanger mounted 10 to rock on the shaft; a segment carried by the second collar; a lever carried by the

second hanger and cooperating with the said segment; and ground wheels journaled on the hangers.

In testimony that I claim the foregoing as 15 my own, I have hereto affixed my signature in the presence of two witnesses.

FRANK HENRY RAAZ.
